UNITED STATES PATENT OFFICE.

WILLIAM L. HANCOCK, OF DALLAS, TEXAS, ASSIGNOR TO THE MURRAY COMPANY, OF DALLAS, TEXAS, A CORPORATION OF TEXAS.

AIR AND COTTON SEPARATOR.

Application filed November 23, 1928. Serial No. 321,400.

This invention relates to new and useful improvements in air and cotton separators.

One object of the invention is to provide a separator of the pocket drum type with a by-pass or duct, arranged to receive a surplus in the feed of cotton to the separator, whereby choking is prevented and a more even distribution of the cotton, as fed to the separator, is obtained.

10 A further object of the invention is to provide a dome on top of the duct capable of relieving a congestion of cotton in the duct and thus accommodating all the cotton fed to the separator.

15 A still further object of the invention is to eliminate valves at the air discharge openings of the casing and to provide in the transition feeding the air and cotton to the casing, an adjustable deflector capable of controlling the feed, whereby the air-cotton currents may enter unimpeded or whereby the air-cotton currents may be diverted or impeded so as to control the feed. Such an arrangement has the advantage of retarding 20 the feed or evening out the flow. Another advantage is that the deflector may be removed when not desired.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a transverse vertical sectional view of a separator constructed in accordance with the invention,

Fig. 2 is a front elevation of the same,

40 Fig. 3 is a plan view of the transition, the deflector being shown in dotted lines,

Fig. 4 is a perspective view of the separator, one end of the casing being removed,

Fig. 5 is a view of the deflector, and

45 Fig. 6 is a transverse vertical sectional view of the transition and deflector.

In the drawings the numeral 10 designates an airtight outer casing which may be of any desired shape and is preferably made 50 of sheet metal. Within the outer casing is an inner casing or cylindrical separating chamber comprising two imperforate curved metal sheets 11 and 12 and two curved foraminous sections 13 and 13' extending upwardly from the rear edge of the sheet 11.

The sheets 11 and 12 with the sections are disposed concentrically and thus define the cylindrical chamber.

Between the bottom edge of the sheet 12 and the front edge of the sheet 11 is formed 60 a vertical cotton chute 14 extending longitudinally of the casing from end to end thereof. This chute is faced along its front side by a sheet metal wall 15 and along its rear side it is closed by a board 16 on the upper 65 edge of which the front edge portion of the sheet 11 is secured. The gap formed in the cylindrical chamber by the chute constitutes the cotton outlet of the same.

Across the top of the front side of the casing is a longitudinal inlet 17, extending substantially from one end of the casing to the other end thereof and being comparatively narrow vertically. A downwardly flared throat 18 extends from the inlet to the upper 75 side of the separating chamber, terminating at the upper edges of the sheet 12 and the sections 13 and 13' and coextensive with the inlet. The upper side of the throat is formed by guide sheets 19.

Within the separating chamber is mounted 80 in suitable bearings 20 at the ends of the casing, a pocket separating drum or valve 21. This drum is equipped with longitudinal radially extending vanes or blades 22, provided with wiping or sealing strips 23 of rubberized belting or other suitable material, as is the usual practice.

These strips project from the outer longitudinal edges of the blades and make continuous contact, throughout their lengths, 90 with the sectors 11, 12 and 13 and 13' of the separating chamber. The sectors 11 and 12 are of such circumferential width that at least one strip 23 is always in contact therewith, so as to prevent an upward passage of air from the chute 14.

The blades 22 form therebetween pockets for receiving the cotton and air from the throat 18 as the drum revolves, the air being released through the foraminous sectors 13 and 13' and the cotton being dumped by gravity into the chute 14.

In the rear of the casing 10 is formed an air manifold 24 having at its bottom a curved 100 guide sheet 25 extending down from the rear edge of the sheet 11 to the rear wall of the said casing. At each end of the bottom of the manifold outlets 26 provided in the rear of the wall of the casing, constitute entrances to 105 110

each end of an air-tight box 27 secured across the rear side of the casing. A suction pipe 28 leads from the rear center of the box and is suitably connected with an air suction fan 5 not shown.

For feeding or conducting air and cotton to the inlet 17, a transition 29 fitting said inlet converges to a circular collar 30 which is connected to the usual conveyor pipe 31. The 10 air-cotton currents drawn into the transition 29, because of the suction from the pipe 28, through the casing, will spread in said transition and discharge into the throat 18 and then pass into the pockets of the drum 21.

15 It is found in actual practice that the supply of cotton is not always uniform and therefore during periods when the flow of cotton is heavy, the machine has a tendency to choke by the pockets and throat becoming full of 20 cotton and air. Also ordinarily when a blade 22 and its sealing strip 23 leave the throat and the strip engages the foraminous sector, the air suction is momentarily cut off and the sealing strip must move a required distance 25 down the section, before a normal air suction is reestablished. Such a condition aggravates choking.

In order to overcome these difficulties a 30 duct 32 is formed at the center of the casing between the sectors 13 and 13' and curving rearwardly and downwardly from the guide sheets 19 contiguous to the separating chamber. The rear wall of the duct is formed by a curved sheet 33 extending from the top of the 35 casing down to the rear edge of the sheet 11.

This duct 32 prevents the air suction from 40 being cut off from the throat 18. The air-cotton currents entering the throat 18 will deposit a considerable part of the cotton in the drum pockets, but said currents are free to pass into the duct 32 and enter the pockets thereunder from said duct. The outlets 26 being at the ends of the manifold 24, induce the currents to flow longitudinally in the 45 drum pockets, thus spreading the cotton longitudinally of the drum.

It has been found that under a peak load 50 the duct 32 is inadequate to relieve choking in the throat 18 of the casing and to care for such emergencies a dome 34 mounted on top of the casing opens into the top of the duct 32, particularly over the throat 18. This dome provides a storage space for a surplus of cotton entering casing which is discharged into 55 the duct and throat, when the congestion is relieved.

Under certain conditions it is desirable to 60 impede the flow of the air-cotton currents through the transition or to deflect the said currents to one side of said transition. For this purpose a separate deflector 35 is provided as is shown in Figs. 3, 5 and 6. This deflector has a curved shank 36 shaped to frictionally engage the inner wall of the collar 30 65 of the transition 39.

The body of the deflector is curved so as to give it a partially cylindrical shape and it is cut back from the shank to a reduced end 37. By observing Fig. 6 it will be seen that the transition has a width vertically substantially equal to the inner diameter of the collar 30. Thus when the deflector is turned, as is shown in Fig. 6, it will have very little effect on the inflowing air-cotton currents. 70

However, by giving the deflector a quarter 75 rotation in the collar 30, it will be brought to the position shown in dotted lines in Fig. 3. In this position the deflector will divert a portion of the inflowing air-cotton currents from the right-hand side (Fig. 3) of the 80 transition, thereby feeding a major portion to the left-hand side. Various adjustments of the deflector may be made to control the spreading of the currents in the transition and throat of the machine. 85

The combination of the elements involved herein makes for continuity of air suction, thus assuring a maximum cotton handling capacity. The air outlets 26 out of register with the suction pipe 28 induce an even distribution of the cotton and air throughout the length of each drum pocket, thus assuring filling of the latter. This is particularly true when coupled with the action of the deflector 90

35. Various changes in the size and shape of the different parts, as well as modifications and alterations, may be made within the scope of the appended claims. 95

What I claim, is:

1. A cotton and air separator comprising, in combination, a casing having an air-cotton inlet and separate air and cotton outlets, a separating chamber within the casing communicating with said inlet and said outlets, a separating drum revolving in said chamber, a transition connected with the inlet of the casing, and rotatable means in the transition for controlling the flow of air-cotton currents therethrough. 100

2. A cotton and air separator comprising, in combination, a casing having an air-cotton inlet and separate air and cotton outlets, a separating chamber within the casing communicating with said inlet and said outlets, a separating drum revolving in said chamber, a transition connected with the inlet of the casing, and a rotatable deflector at the entrance of the transition adjustable to cause various deflections of the inflowing air-cotton currents. 115

3. As a sub-combination in an air and cotton separator, a transition for connection to the inlet of the casing having a collar at its reduced end, and a deflector having a shank rotatable in said collar and a body extending into the transition. 120

4. A cotton and air separator comprising, in combination, a casing having an air-cotton inlet and separate air and cotton outlets, a 125

separating chamber within the casing communicating with said inlet and said outlets, a separating drum revolving in said chamber, a throat in the casing extending from the inlet to the chamber and disposed longitudinally of the casing for conducting air-cotton currents to the chamber, a transverse duct in the casing extending from the throat and contiguous to the separating chamber for receiving and conducting an overflow of air and cotton from the throat to the drum, a transverse dome on the casing communicating with the top of the duct for receiving and storing an overflow of air and cotton from the duct, a transition connected to the inlet of the casing, and a deflector mounted in the transition for controlling the passage of air-cotton currents to the casing.

5. A cotton and air separator comprising, in combination, a casing having an air-cotton inlet and separate air and cotton outlets, a separating chamber within the casing communicating with said inlet and said outlets, a separating drum revolving in said chamber, a manifold within the casing, the air outlets of said casing being located at each end of said manifold, the separating chamber hav-

ing a foraminous sector for establishing air connection with the manifold, a transition connected to the inlet of the casing, and means in the transition for directing a major portion of the inflowing air-cotton currents toward one end of the casing, said means being rotatable to direct said currents to either side of the casing.

6. A cotton and air separator comprising in combination, a casing having an air-cotton inlet with a feed throat communicating therewith and separate air and cotton outlets, a separating chamber within the casing communicating with the inlet feed throat and said outlets, a separating drum revolving in said chamber, a duct in the casing circumferential to a portion of the chamber and extending rearwardly from the feed throat for receiving an overflow of cotton therefrom, and a dome on the casing upwardly above the throat at the inlet to the duct and rearwardly for a portion of the length of the duct for providing a relief chamber for excess to prevent packing in the duct and to feed by gravity to said throat.

In testimony whereof I affix my signature.

WILLIAM L. HANCOCK.
